UNITED STATES PATENT OFFICE.

SAMUEL H. POLLOCK, OF ROCKY FORD, COLORADO.

ARTIFICIAL TOOTH.

1,099,393.

Specification of Letters Patent.

Patented June 9, 1914.

Application filed July 18, 1913. Serial No. 779,807.

To all whom it may concern:

Be it known that I, SAMUEL H. POLLOCK, a citizen of the United States, residing at Rocky Ford, in the county of Otero and 5 State of Colorado, have invented a new and useful Artificial Tooth, of which the following is a specification.

The present invention appertains to an artificial tooth, and relates more particularly to what has become known in the art 10 as a porcelain crown.

It is the object of the present invention to provide novel and improved means for anchoring the crown to the root or stub of a 15 tooth.

Another object of the present invention is to provide a crown adapted to be anchored to a root, and so constructed, that a bridge 20 may be readily soldered or attached thereto for supporting another tooth or a plurality of teeth.

A further object of the present invention is to provide a device of the nature indicated which will provide a comparatively 25 strong and efficient tooth, the construction being relatively simple and inexpensive, and the crown being readily applicable to different roots.

With the foregoing general objects outlined and with other objects in view, which will be apparent as the nature of the invention is better understood, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention has been illustrated in its preferred embodiment in the accompanying drawing, wherein:

Figure 1 is a side elevation of the improved crown. Fig. 2 is a front view of the crown. Fig. 3 is a rear or lingual view of the crown. Fig. 4 is a sectional view of the crown as applied to a root. Fig. 5 is a perspective view of the body portion of the crown. Fig. 6 is a perspective view of the backing of the crown. Fig. 7 is a perspective view of the crown pin.

In carrying out the present invention, there is provided a body portion or crown 55 proper 1 of porcelain or other refractory material, and which is commonly termed a "porcelain crown". The basal portion of

the crown 1 is relatively large, or is of a contour approximately the same as that of the base of the root, while the free or outer portion of the crown has a cutting edge 60 similar to an anterior tooth. The back or lingual side of the crown 1 is preferably concaved between the extremities of the crown, and the basal portion of the facing 65 is preferably countersunk as at 3. The crown 1 is provided with a diagonal bore 4 extending from its lingual side to the base, so that the bore may be said to extend diagonally from the lingual side to the base. 70 The bore 4 is preferably of circular cross section, and terminates centrally of the counter sunk portion 3. The bore 4 is also preferably, although not necessarily, curved 75 slightly.

In connection with the crown 1, there is employed a backing 5, of gold or any other suitable metal or material. The backing 5 is comparatively thin and is shaped to conform to the lingual side of the crown, the 80 edges or marginal portions of the backing being flanged or worked over the edges of the lingual side of the crown. Attached at an acute angle to the backing 5 is a tubular or socket member 6, of any suitable 85 metal, preferably such as is inexpensive and non-corrosive, and preferably having internal grooves or notches. The tube or socket 6 is adapted to slip upwardly within the bore 4 of the crown, in order that the free end of 90 the tube or socket will become flush with the counter sunk portion 3. The tube or socket 6 is also preferably curved slightly to conform to the curvature of the bore 4.

The numeral 7 designates the pin which 95 is adapted to be inserted into the root canal or cavity, the pin being preferably flat and tapered, and having the transverse depressions 8 in its sides. The pin 7 is provided with the head or flange 9 at its butt end, 100 and is further provided with a short shank 10 projecting from the head 9. The shank 10 is preferably circular in cross section and of a diameter slightly smaller than the internal cross section of the tube or socket 6. 105 The shank 10 is provided with a plurality of annular or circumferential grooves 11 forming collars or shoulders 12. The shank 10 is also curved slightly to conform to the curvatures of the tube 6 and bore 4. The 110 pin 7 may be constructed of any suitable metal adapted for the purposes for which it is employed.

A tooth root 13 has been illustrated in

Fig. 4, the same having the ordinary canal or cavity 14, which is designed or adapted to receive the pin 7.

The present crown is applied to the root as follows:—After the natural tooth has been properly broken away to expose the root canal or cavity, and after the said canal or cavity has been properly treated, the pin 7 is secured within the canal 14 by means of suitable cement 15. The pin may be readily cemented within the root canal, the cement working into the depressions or grooves 8 of the pin to securely lock or anchor the pin within the root, with the head 9 and shank 10 of the pin exposed. The shank 10, when the same is curved, is set so as to project rearwardly, as seen in Fig. 4. It is to be understood, of course, that the pin is properly positioned before the cement 20 sets or hardens. Then, after the tube or socket 6 of the backing has been inserted into the bore of the crown, the said facing and backing may be applied to the shank of the pin to test the crown. If the crown 25 is untrue with respect to the root, the same may be readily ground to shape in a manner which will be apparent to those versed in the art. It is to be observed that the crown embodying the backing may be readily 30 slipped onto and off of the shank of the pin without creating any undue strain upon the root. After the crown has been properly ground or shaped, the same, together with the backing, is secured in place. This 35 is accomplished by placing any suitable cement 16 between the crown and the root when the crown is applied, the cement running or flowing into the tube 6 also. Then as the crown is slid or forced home, the tube 40 in receiving the shank of the pin, will cause the cement within the tube to enter the grooves 11 of the shank, and will cause that portion of the cement between the crown and root to conform to the irregularities of 45 the adjoining portions of the crown and root. The superfluous cement is then wiped away, and after the cement has hardened or set, the crown will be rigidly anchored to the root. The tooth thus provided will be 50 very rigid and durable, it being noted that the crown is not only cemented to the root, but is held by the backing which has the tube passing through the crown and secured over the shank of the pin. The present 55 tooth is adapted to resist the strains to which it is subjected, such as the strain of mastication, in an effective manner. If desired, the backing may be extended over the incisive edge of the crown, so that the backing 60 will directly receive the strains of mastication.

The present tooth or crown, is particu-

larly useful in connection with bridgework, the present crown being adapted to replace an anterior tooth, by breaking the anterior tooth away, so that the present crown may be applied as above indicated. When the present crown is applied, it will be observed that the backing may serve as an abutment for the attachment of a bridge or other support for the other tooth or teeth.

The present crown or tooth, may even be removed from the pin after the crown has been cemented in position. This may be accomplished by prying or otherwise loosening the crown from the tooth, the crown being twisted or otherwise loosened from the shank of the anchor pin. Attention is directed to the fact that the anchor pin is permanently secured within the root, while the crown is detachably secured to the anchor pin. This is of advantage in permitting the crown to be attached and detached from the root, and also permitting the crown to be readily ground without the interference of the anchor pin. The backing may be strengthened to any extent desired, by applying gold solder thereto, or its equivalent, the backing and crown being detachable to permit the application of the solder to the backing without heating the crown. The present crown may be employed with or without a cap or band to embrace the junction between the crown and the root.

Having thus described the invention, what is claimed as new is:—

1. In an artificial tooth, a crown having a bore therethrough, a root-engaging anchor pin, and a crown backing, the anchor pin and backing having members adapted to be received by the said bore and to be secured together therein.
2. In an artificial tooth, a root-engaging anchor pin, and a crown backing, a crown having a bore therethrough, one of the two first mentioned parts having a socket insertible into the said bore, and the other of the two first mentioned parts having a portion insertible into the said socket.
3. In an artificial tooth, a crown having a diagonal bore therethrough, a backing having an integral tube arranged at an acute angle relative thereto and insertible into the said bore, and a root-engaging anchor pin having a shank insertible into the said tube to be secured therein.

In testimony that I claim the foregoing as my own, I have hereto affixed my signature in the presence of two witnesses.

SAMUEL H. POLLOCK.
